CLAIM

We claim the ornamental design for an alarm, as shown and described.

DESCRIPTION

FIG. 1 is a front perspective view of an alarm.

FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof; and,

FIG. 7 is a right side elevation view thereof.

In the drawings, the broken lines depict portions of the alarm that form no part of the claimed design.
